UNITED STATES PATENT OFFICE.

EDMUND N. BROWN, OF SAN FRANCISCO, CALIFORNIA, ASSIGNOR TO MAJESTIC ELECTRIC DEVELOPMENT COMPANY, A CORPORATION OF CALIFORNIA.

DESIGN FOR AN ELECTRIC-HEATER CASING.

51,328.

Specification for Design.

Patented Oct. 9, 1917.

Application filed August 22, 1917. Serial No. 187,677. Term of patent 7 years.

To all whom it may concern:

Be it known that I, EDMUND N. BROWN, a citizen of the United States, residing at San Francisco, in the county of San Francisco and State of California, have invented a new, original, and ornamental Design for Electric-Heater Casings, of which the following is a specification, reference being had to the accompanying drawing, forming part thereof.

The figure is a front perspective view of an electric heater casing showing my new design.

I claim:—

The ornamental design for an electric heater casing substantially as shown.

In testimony whereof I affix my signature.

EDMUND N. BROWN.
